UNITED STATES PATENT OFFICE.

CHARLES G. W. NITZ, OF WAUWATOSA, WISCONSIN.

RATCHET-DRILL.

1,241,428.

Specification of Letters Patent. Patented Sept. 25, 1917.

Application filed January 17, 1917. Serial No. 142,908.

To all whom it may concern:

Be it known that I, CHARLES G. W. NITZ, a citizen of the United States, residing at Wauwatosa, in the county of Milwaukee and State of Wisconsin, have invented certain new and useful Improvements in Ratchet-Drills, of which the following is a specification.

This invention relates to ratchet drills, and particularly to that class of tools which are designed to be used manually for rotating a drill by the movement of a handle transversely through the axis of the drill. This invention having for its object to provide a drill of such a type with a double ratchet whereby the drilling tool may be caused to rotate in two directions, and to provide such ratchet means with a simple device for setting the pawls to optionally rotate the drill in one or the other direction with each movement of the handle; to move the drill with every alternate movement of the handle, and in the same direction; or to move the drill in a direction opposite to that in which the handle is moved, the movement of the handle being understood to refer to that movement to which power is applied.

A further object of the invention is to provide a ratchet drill of the type set forth which shall be relatively simple in construction, of few parts and thoroughly strong for the purpose demanded, and which may be adjusted without trouble to cause the drill point to move in the direction and in the manner desired.

With the above as the principal objects in view, the invention consists in the novel construction, combination and arrangement of parts hereafter described, pointed out in the appended claims and illustrated in the accompanying drawing, wherein, for the purpose of description, that part of the tool uppermost in Fig. 2 will be called the top and the opposite side the bottom.

In the drawings—

Figure 1 is a top plan view of the improved drill,

Fig. 2 is an elevation of the same as seen from the right of Fig. 1,

Fig. 3 is a vertical central longitudinal section on the line 3—3 of Fig. 1,

Fig. 4 is a transverse horizontal sectional view on the line 4—4 of Fig. 3,

Fig. 5 is a vertical cross sectional view on the line 5—5 of Fig. 1,

Fig. 6 is a horizontal sectional view on the line 6—6 of Fig. 3, looking upwardly,

Fig. 7 is a detail sectional view through the lower end of the tool on the line 7—7 of Fig. 5, and

Fig. 8 is a detail perspective view of the pawl setting mechanism.

In the drawings, 10 indicates a hollow socket open at its upper end and closed at its lower end from which two or more pins 11 project, said pins being sharpened and designed to penetrate substantially into a backing to hold the socket 10 from rotation when the drill is in operation.

Fitted over the upper end of the socket 10 is a casing 12 that contains the various mechanisms for operating the drill. The casing 12 may be said to consist of two parts, a cylindrical portion 13 axially mounted on the socket 10 to vibrate transversely thereon and a projection 14 at one side to which is secured a handle 15 of indefinite length for actuating the casing and through the casing rotating the drill. The casing 12 is closed at its sides and lower end and open at the top, the cylindrical portion 13 being provided with a closure 16, the edge of which is threaded to screw into the top of the casing and is provided with a flange 17 at its top to overhang the side of the casing. The projection 14 of the casing is closed by a plate 18 which may be secured in place by screws 19 or other means passing therethrough and into the sides of the projection.

The socket 10 is provided with a straight longitudinal bore 20 within which is rotatably fitted a straight cylindrical shell 21 adapted to rotate in said bore and project through the top of the socket and through the closure 16 of the casing, the shell turning freely in said closure and is preferably formed with an enlargement 22 on its upper end, and flat on its top to form a bearing surface for an adjusting nut 23, the use of which will be described later. To enable the shell to turn easily within the socket an anti-friction bearing in the form of a ball 24 is seated in a semi-circular seat in the bottom of the socket and of the shell, the shell being slightly separated from the socket at the bottom and supported wholly upon the ball as shown.

The shell 21 has a straight bore 25 that extends from its upper end normally to the ball 24 within which bore 25 is placed a

Chuck 26 having a tapered upper end to receive the similar tapered shank 27 of a drill. The chuck 26 is exteriorly threaded from end to end and upon it is secured the 5 adjusting nut 23 which upon being rotated moves the chuck longitudinally, and thus provides means for feeding the drill when operating the same. To prevent rotation of the chuck within the shell 21, one or two 10 longitudinal grooves 28 are cut through the threaded portion of the chuck through the sides thereof, in which groove, ribs 29, formed upon or secured to the shell 21 within the bore 25, are adapted to slide easily. 15 Within the cylindrical portion 13 of the casing and near the bottom thereof is a ratchet wheel 30 mounted upon the socket 10 to rotate freely thereupon. A second ratchet wheel 31 is concentrically arranged 20 with respect to the ratchet wheel 30 just below the closure 16 of the casing and is rigid with the shell 21, being secured thereto by one or more keys 32 so that upon rotation of the ratchet wheel 31 the shell will also 25 turn and with the shell the chuck 26 and the drill mounted therein. On the facing side of the ratchet wheels 30 and 31 are gear rings 33 and 34 of equal diameter and pitch, said gear rings meshing with two pinions 35 and 36 diametrically disposed on opposite sides of the upper end of the socket 19 and journaled on pins 37 screwed into the socket near the top, said pins preferably having enlarged heads 38 as shown to maintain 30 the pinions in place. As thus arranged, movement of either ratchet wheel in one direction will, through the pinions 35 and 36, cause a rotation of the other ratchet wheel in a reverse direction. 35 Movement is imparted to the ratchet wheels 30 and 31 by means of pawls pivoted in the casing 12, there being two pawls 40 and 41 adapted to actuate the ratchet wheel 30 and two like pawls 42 and 43 to engage 40 the upper ratchet wheel 31. The pawl 42 is immediately above the pawl 40 and both are mounted to rock on a pin or shaft 44 seated at its lower end in the bottom of the casing extension 14 and at its upper end in 45 the closure 18 therefor. Pawls 41 and 43 are similarly mounted to rock on a vertical shaft 45 supported in the same manner. The shafts 44 and 45 are spaced apart a short distance and the pawls extend therefrom toward 50 the ratchet wheels at a downwardly extending angle as clearly shown in Fig. 4, thereby permitting shifting means being placed between said pawls. 55 The shifting means of the present invention 60 comprises a vertical shaft 46 rotatably mounted in the bottom of the casing extension 14 and the closure 18 projecting through said closure, its upper end being finished with a thumb nut or disk 47 by 65 means of which the shaft may be turned.

Fixed on the lower end of the shaft 46 is a disk 48 between the pawls 40 and 41. A similar disk 49 is secured to the shaft between the pawls 42 and 43. Each of said disks is provided with peripheral notches 50 and 51, respectively, notches 50 serving to receive lugs 52 on the pawls 40 and 41, the notches 51 in the upper disk co-operating with lugs 53 on the inner faces of the pawls 42 and 43. Between the lower pawls is a contractile spring 54, a similar spring 55 connecting the upper pawls, these springs serving to hold the pawls at all times in contact with the disks 48 and 49, and whenever a notch 50 or 51 aligns with a lug 52 or 53 one or the other of said contractile springs will draw the pawl carrying said lug inwardly across the free end of the pawl to engage a ratchet wheel. To indicate to the operator the position of the pawl, the shaft 46 is provided with a pointer 56 that rotates with said shaft over a scale 57 on the upper side of the closure 18 and thus points out to the operator which of the pawls are in engagement with the ratchet wheels and the movement to be expected of the drill upon transverse movement of the handle 15. As indicated in the drawing, the drill is set to turn to the right with each forward and backward movement of the handle. The shifter may be further turned into such position as to act on the pawls to cause their engagement with the ratchet wheel for the purpose of turning the drill to the left with each double movement of the handle, and upon further turning of the shifter to cause movement of the drill to the right or the left when the handle is moved in one direction only.

In the operation of the tool a drill shank 27 is seated in the chuck 26 and the point of said drill placed against the work in the usual manner and tightly held in place by a backing that bears upon the points 11. By this means the drill will be held firmly in place and may be placed as represented in the drawing horizontally or at any angle desired. The operator then moves the handle 15 back and forth about the axis of the drill which causes such pawls as are set to engage the ratchet wheels and intermittently rotate the drill. Rotating the nut 23 as the drill cuts causes the advance of the drill in the usual manner.

When the pawls are set as shown in the drawing, particularly in Fig. 8, it will be noted that the shaft 46 of the shifting device is turned into such position that the lug 53 on the pawl 42 is aligned with a notch in the disk 49, and as a consequence, the spring 55 drawing on said pawl causes the free end of the latter to engage the upper ratchet wheel 37. For a similar reason the lug 52 on the lower pawl 41 on the opposite side of the shaft 46 is also aligned with a

- notch in disk 48, and as a consequence said latter pawl is in operative engagement with the lower ratchet wheel 30. As a result of this position of pawls 41 and 42 movement of the handle 15 in either direction will through the pivoted connection of said pawls with the handle rotate the upper ratchet wheel to the right or clockwise when moved in one direction and cause a reverse 10 rotation of the lower ratchet wheel 30 when the handle is moved in the opposite direction. This latter movement, however, being imparted to a ratchet wheel rotatable loosely about the socket 10, will through the pinions 35 and 36 cause the upper ratchet 31 to continue its movement to the right which ratchet being keyed to the shell 21 and the latter to the chuck 26, rotary motion will be imparted to the drill. 15
- Should it be desired to rotate the drill in the opposite direction, the shaft 46 would be turned sufficiently to cause the pawls 40 and 43 to engage the ratchet wheels 30 and 31, thus causing the drill to be turned 20 to the left or counterclockwise by the same movement of the handle. Other movements of the shaft 46 will so operate upon the disks 48 and 49 as to cause them to engage the ratchet wheel and cause a movement 25 only when the handle is moved in one direction, there being a slip of the ratchet during the opposite movement of the handle. 30
- I claim:
1. The combination in a ratchet drill, of a chuck, a ratchet wheel keyed to said chuck, a second ratchet wheel concentric with the first ratchet and rotatable freely about said chuck, gearing between said ratchet wheels for causing their rotation in opposite directions, an operating handle adapted to rotate about said chuck, two pairs of pawls carried by said handle, each pair adapted to coöperate with one of said ratchet wheels, and rotating means carried by said handle 45 for moving said pawls into and out of engagement with the ratchet wheels.
  2. The combination in a ratchet drill, of a chuck, a ratchet wheel keyed to said chuck, a second ratchet wheel concentric with the first ratchet wheel and rotatable freely about said chuck, a gear ring on each ratchet wheel, a pinion meshing with said gear rings, a pair of pawls adapted to operate each of said ratchet-wheels, an operating 50 handle turning on said chuck and supporting said pawls, a contractile spring between each of said pairs of pawls, a rotatable shifting device between each pair of pawls, a shaft turning in said handle to which said shifting devices are secured and by means of which said pawls are moved into and out of engagement with the ratchet wheels. 55
  3. The combination in a ratchet drill, of a socket, a chuck mounted to rotate freely within said socket, a ratchet wheel keyed to
  4. The combination in a ratchet drill, of a socket, a chuck mounted to rotate freely within said socket, means for moving said chuck longitudinally as desired, a ratchet wheel keyed to said chuck for rotating the same, a second ratchet wheel concentric with the first ratchet wheel and rotatable freely 80 about said chuck, a gear ring on each of said ratchet wheels, a pinion meshing with said gear rings for causing opposite rotation of said ratchet wheels, bearing pins projecting from said socket for rotatably supporting said pinions, a pair of pawls movable into engagement with each ratchet wheel for causing rotation thereof, and a rotatable shifting device between each pair of pawls for optionally engaging one or the other with said ratchet wheel to vary the movement of the chuck. 85
  5. The combination in a ratchet drill, of a casing, a socket projecting from one side of said casing and rotatable therein, a chuck 100 longitudinally movable in said socket, a pair of ratchet wheels surrounding said chuck, one of which is keyed thereto, a gear ring on the facing side of each ratchet wheel, pinions meshing with said gear rings for 105 causing opposite rotation of said ratchet wheels, bearing means projecting from said socket for rotatably supporting said pinions, a pair of pawls for each ratchet wheel mounted within said casing, and a shifting 110 device operable on said pawls for optionally moving the same into engagement with the ratchet wheels to vary the movement of the chuck. 115
  6. The combination in a ratchet drill, of a casing, a socket projecting from one side of said casing and rotatable therein, a shell 120 rotatably supported at one end in said socket and projecting at its opposite end through the casing, a threaded chuck slideable longitudinally in said shell and extending beyond the outer end of the same, a ratchet wheel keyed on said shell, a similar ratchet wheel loose about the socket, a gearing between said ratchet wheels, a pair 125 of pawls for each ratchet wheel, and a shifting mechanism for optionally engaging the pawls with the ratchet wheels to vary the movement of the chuck. 130
  7. The combination in a ratchet drill, of

a casing, a socket projecting from one side of said casing and rotatable therein, a shell concentric and rotatably mounted within said socket and projecting from the opposite sides of said casing, a threaded chuck freely slidable in a longitudinal direction in said shell and extending beyond the outer end of the same, means between said shell and said chuck for causing rotation of the latter when the shell is turned, an adjustable nut threaded on said chuck for moving the latter longitudinally, a ratchet wheel keyed on said shell, a similar ratchet wheel loose

upon the socket, gearing between said ratchet wheels, a pair of pawls for each ratchet wheel, and shifting mechanism for optionally engaging the pawls with the ratchet wheels to vary the movement of the chuck.

In testimony whereof I affix my signature in presence of two witnesses.
